UNITED STATES PATENT OFFICE

2,346,827

SWEATBOX

Milton A. Cotter, Los Angeles, Calif.

Application January 26, 1942, Serial No. 428,232

7 Claims. (Cl. 4—163)

This invention relates to sweat boxes in which patients are given sweat baths.

The principal object of the invention is to provide a sweat box in which a patient may be given a sweat bath without any weakening effects.

A more particular object of the invention is to provide a sweat box in which the patient may rest in a reclining position while taking a sweat bath.

Another object is to provide a sweat box which will admit fresh oxygen to the patient as fast as oxygen is used up by the patient's skin, and will permit the waste gases from the patient to be expelled from the sweat box as fast as the pores of the patient's skin throw off said gases, thus allowing the patient to sweat with the greatest comfort.

Another object is to provide a sweat box mounted on casters, so that the sweat box, with a patient resting therein, may be rolled from a dressing room to a special room from which the sweat box and the patient therein may be rolled back into the dressing room after the patient has completed his sweat bath.

Another object is to provide a sweat box of the character stated which is collapsible, so that it may be readily taken down and stored in a small space, or set up in position for use as desired.

Another object is to provide a sweat box of the character stated with improved steam distribution.

Another object is to provide a sweat box with a canvas top through which the sweat box is ventilated.

Another object is to provide a sweat box with a canvas bed for supporting the patient in a reclining position in the sweat box, whereby the patient rests while taking a sweat bath.

Another object is to provide a sweat box with openings in the top wall thereof, through which openings the patient may extend his hands when he desires to use them outside of the sweat box for any purpose.

Another object is to provide a sweat box in which the heat may be controlled by the patient inside of the sweat box, or by a nurse outside of the sweat box.

Other objects and advantages will appear hereinafter, and while I disclose my invention in the form which I consider the best, I do not limit my invention to such form, because it may be embodied in other forms, and it is to be understood that in and by the claims of this specification I

intend to cover my invention in whatever form it may be embodied.

The invention is illustrated in the annexed drawings which form a part of this specification and in which:

Fig. 1 is a vertical longitudinal section of my invention taken on line 1—1 of Fig. 4, showing a patient supported in a reclining position therein.

Fig. 2 is a transverse vertical section of my invention taken on line 2—2 of Fig. 1.

Fig. 3 is a transverse vertical section of my invention taken on line 3—3 of Fig. 1.

Fig. 4 is a plan view of my invention, partly broken away to show certain features of construction.

Fig. 5 is an enlarged fragmentary vertical longitudinal section taken on line 1—1 of Fig. 4 illustrating the cover of my sweat box.

Fig. 6 is an enlarged fragmentary longitudinal section, taken on line 1—1 of Fig. 4, of the foot end of the bed, showing how said end of the bed is detachably mounted in the sweat box.

Fig. 6a is an enlarged fragmentary longitudinal section, taken on line 1—1 of Fig. 4, of the head end of the bed.

Fig. 7 is an enlarged fragmentary face view of the head end wall of my sweat box, showing the openings through which are extended the wires and switch of the electric heating circuit of my sweat box and showing the cover for the switch opening.

Fig. 8 is a vertical section taken on line 8—8 of Fig. 7.

Figs. 9 and 10 are a perspective of two of my sweat boxes arranged side by side with a man in one box and a woman in the other box taking sweat baths.

Fig. 11 shows a head member for the bed.

Fig. 12 shows a clamp bar for the head member.

Fig. 13 shows an adjustable seat bar.

Fig. 14 is a cross-section on line 14—14 of Fig. 13.

Fig. 15 is another view of the cover and supporting frames shown in Fig. 5, parts being broken away.

Referring more particularly to the drawings, in which corresponding parts are designated by the same reference numerals in all of the views, my sweat box includes a box 1, formed with a bottom wall 2 mounted on swiveled casters 3, side walls 4, head end wall 5, foot end wall 6, and a canvas top wall or cover 7. A steam generator 8 is supported on said bottom wall, and a false bottom 9 is mounted on said bottom wall over said steam heating unit. A bed 10 is mounted in the box 1.

above said false bottom. An electrical heating circuit 11, controlled by a switch 12, supplies heat to said steam generator 8.

To the edges of the bottom wall 1 are secured angle irons 13, with the horizontal flanges of said angle irons extending under the bottom wall and the vertical flanges of said angle irons extending upwardly over the edges respectively of said bottom wall. The lower edges of the end walls 5 and 6 rest upon the bottom wall 1 against the inner sides of the vertical flanges of the angle irons 13 along the ends, respectively, of said bottom wall. The lower edges of the side walls 3 and 4 rest upon the bottom wall 1 against the inner sides of the vertical flanges of the angle irons 13 along the side edges, respectively, of said bottom wall, with the inner sides of said side walls, at their ends, resting against the side edges of the end walls 5 and 6, whereby said side walls are prevented from falling inwardly. Angle irons 14 are secured on the ends of the side walls 4 so that one flange of said angle irons fit over the side edges of the end walls 5 and 6 outside of said end walls, when the side walls and end walls are set up in position on the bottom wall 1, thus forming steam tight joints between the ends of the side walls and the sides of the end walls, as shown in Fig. 9 of the drawings. Each of the side walls 4 is made in two longitudinal sections, a lower section 15 and an upper section 16, the lower edge of the upper section being hinged to the upper edge of said lower section by a hinge 17, so that the upper section of either side wall may be swung outwardly and down, as illustrated in Figs. 2 and 3 of the drawings, to permit the patient to get into or out of the sweat box easily at either side thereof. Spring slide bolts 18 are mounted on the inner side near the upper corners of the upper hinged section 16 of each side wall 4, for engaging catches 19 in the end walls 5 and 6, respectively, of the sweat box, for detachably holding said hinged sections swung up into closed position, as shown in full lines in Figs. 2 and 3. A chain 20 is connected, at one end, to the inner end of each slide bolt 18, and at its other end, at 21, to the inner side of the upper hinged section 16 on which said slide bolt is mounted, so that the patient, reclining on the bed 10 in the sweat box, may pull the two chains 20 connected to the slide bolts 18 on the upper hinged section 16 of either side wall 4, to withdraw said slide bolts from catches 19, in the end walls 5 or 6, respectively, and thereby release the upper hinged section of either side wall, whereupon the patient may swing down the released upper hinged section of the side wall 4 and step out of the sweat box from the side at which said upper section is swung down.

The steam generator 8 includes a steam generating chamber 22, an electric heater 23 mounted in said chamber, a steam pipe 24 leading from said steam generating chamber, and a steam condensing chamber 25, open at the top, into the top of which leads said steam pipe, said chambers being mounted within the sweat box upon the bottom wall 1 thereof. Electric current is supplied to the electric heater 23 by the heating circuit 11, through its wires 26 and 27 and switch 12, to which said wires are connected intermediate their ends, one end of said wires being connected to the terminals of the heater 23, and the other end of said wires being connected to a plug coupling 28 which may be introduced into a wall socket 29 of a conventional service circuit. The

head end wall 5 is provided with an opening 30, through which the wires 26 and 27 extend, and with an enlarged opening 31 communicating with said opening 30, through which enlarged opening 31 the switch 12 may be drawn into the sweat box, to be actuated by the patient within the sweat box, or drawn out of the sweat box, to be actuated by a nurse or an attendant outside of the sweat box. The enlarged opening 31 is normally closed by a cover 32, which is held over the outside of said opening by spring clips 33 secured to the inner side of said cover and adapted to extend into said enlarged opening 31 and engage the edge thereof.

15 The false bottom 9 is pivotally mounted at its ends respectively at 34, on the upper ends of rectangular-shaped heavy-wire legs 25, the lower ends of which legs rest upon the bottom wall 1 of the sweat box, at the ends, respectively, of said bottom wall, and support said false bottom in position immediately above the steam generator 8. The false bottom 9 is shorter in length than the length of the sweat box, so that said false bottom may be moved lengthwise in one direction or the other on its legs 35, which swing correspondingly from their lower ends and on their pivots 34 with relation to said false bottom, to permit such lengthwise movement of said false bottom, until one end of said false bottom abuts against one of the end walls 4 or 5 of the sweat box, leaving a space 36 between the other end of said false bottom and said other end wall, as shown in Fig. 1, through which space 36 steam passes from the steam generator 8 under the false bottom 9 upwardly into one end of the sweat box above said false bottom. Said false bottom is of less width than the width of the sweat box, to provide longitudinal spaces 37 between the side edges of the false bottom and the side walls 4, respectively, of the sweat box, through which spaces steam passes from the steam generator 8 under the false bottom 9 upwardly in the sweat box at its sides, respectively, and said steam is thus directed laterally from both sides of the sweat box upon the body of the patient reclining in the bed 10 in the sweat box.

40 The bed 10 comprises a head member 38, a foot member 39, a seat member 40 and a flexible bottom member 41. Said head member 38 comprises a pair of sockets 42 and 43, secured to the inner side of the lower section 15 of each side wall 5 and 6 of the sweat box, a pair of corner posts 44, each of which is supported in a pair of said sockets 42 and 43 at one side of the sweat box, a transverse horizontal channel head bar 45 detachably mounted at its ends on the upper ends of said corner posts, respectively, and a clamp bar 46 to be received by said channel bar for clamping the head end of the flexible bottom member 41 of the bed 10 in said channel bar. The upper ends of the corner posts 44 are formed with sockets 47, respectively, to receive shanks 48 depending from the ends, respectively, of the channel bar 45, whereby said channel bar is detachably mounted on the upper ends of said corner posts. The sockets 43 are secured on the upper sections 16, of the side walls 4, respectively, above the sockets 42, and are engaged by lugs 49 on the corner posts 44, respectively, for arresting said corner posts in said sockets in position for supporting the channel bar 45 horizontally at its proper height. The foot member 39 comprises a pair of sockets 50, secured to the inner sides near the upper edges of the upper sections 16 of the side walls 4, respectively, a transverse channel

foot bar 51, detachably mounted at its ends in said sockets, respectively, and a clamp bar 52 to be received by said channel bar, for clamping the foot end of the flexible bottom member 41 of the bed 10 in said channel bar. The channel bar 51 is formed with a pair of shanks 53 depending from its ends, respectively, which shanks are introduced into the sockets 50, respectively, whereby said channel bar is detachably mounted in said sockets. The seat member 40 comprises a transverse seat bar 54 and a pair of angle iron brackets 55 secured to the inner sides near the upper edges of the lower sections 15 of the side walls 4, respectively, of the sweat box, upon which angle bars rest the ends, respectively, of said seat bar, there being a plurality of longitudinally spaced openings 56 in the supporting flanges of said angle bars to receive two pins 57 depending from the ends, respectively, of said seat bar, whereby said seat bar is adjustably supported in different positions between the head member 38 and foot member 39 of the bed 10. The seat bar 54, connected at its ends to the angle brackets 55 on the lower sections 15 of the side walls 4, holds said side wall sections together between their ends in parallel relation, so that said lower sections of said side walls cannot be moved inwardly, the vertical flanges of the angle irons 13 along the side edges of the bottom wall 1 preventing outward movement of said side walls. The flexible bottom member 41 of the bed is preferably a sheet of canvas which is placed over the seat bar 54, with its ends extended over and under the clamp bars 46 and 52, respectively, and said clamp bars placed in the channel bars 45 and 51 respectively, whereby the ends of said sheet of canvas are detachably and adjustably secured to the head member 38 and foot member 39, respectively, of the bed 10.

The top wall or cover 7 of the sweat box comprises two square frames 60 and 61 and a sheet of canvas 62 extending over said frames and partly under the same. Over the upper edges of the side walls 4, and the end walls 5 and 6 of the sweat box are fitted metal edge members 63 formed with internal horizontal flanges 64 extending inwardly into the sweat box a short distance below said upper edges of said side walls and said end walls, upon which flanges rest said frames 60 and 61, the outer transverse end rails 65 and 66 of said frames, respectively, resting upon the flanges 64 of the edge members 63 of the end walls 5 and 6, and the longitudinal side rails 67 and 68 of said frames 60 and 61, respectively, resting upon the flanges 64 of the edge members 63 of the side walls 4 of the sweat box, with the inner transverse rails 69 and 70 of said frames 60 and 61, respectively, positioned adjacent each other in parallel relation as illustrated in Fig. 5 of the drawings. Pins 71 extend downwardly from the inner corners, respectively, of the frame 60 through openings 72 in the flanges 64 of the edge members 63 of the side walls 4, respectively, whereby said frame 60 is held in position against longitudinal movement away from the end wall 5 of the sweat box when the frame 61 and the canvas sheet 62 thereon are swung up as illustrated in Fig. 5. The canvas sheet 62 is provided with a head opening 73 and with a pair of arm openings 74, and said sheet is provided with a slit 75 extending from said head opening and closed by a zipper 76 when the head of the patient is extended through said head opening, and weighted flaps 77 are secured at one

side to a side edge of the arm openings 74, respectively, for normally closing said arm openings.

The operation of my invention is as follows:

To give a patient a sweat bath in my sweat box, the top wall 7 of the sweat box is first folded upon itself, by swinging the half of said wall on the frame 60 upwardly over the other half of said wall on the frame 61, and the top wall, thus folded, is lifted off the flanges 64 of the upper edge members 63 of the sweat box and moved slightly rearwardly and to one side of the sweat box and placed upon the upper edge of the foot end wall 6 and the upper edge of one of the side walls 4, leaving the upper edge of the other side wall 15 free; the slide bolts 18 on said other side wall 4, are then withdrawn from catches 19 in the end walls 5 and 6 upon pulling the chains 20 connected to said bolts, and the upper section 16 of said side wall 4 is then swung outwardly and 20 down on its hinge 17; the patient then gets into the sweat box and the bed 10 through the upper open portion of the side of the box having the upper section 16 of its side wall 4 swung down as aforesaid, and the patient reclines in the bed upon the canvas bottom 41 thereof, with his head extending out of the top of the box and above the upper edge of the head end wall 5 of the box, as shown in Fig. 1 of the drawings; the upper section 16 of the side wall 4 which is swung up 25 into its vertical and closed position, and the spring slide bolts 18 are sprung over catches 19 in the end walls 5 and 6 whereby said upper section 16 is locked in its vertical and closed position on the sweat box; the top wall 7, in its folded position 30 as above described, is then shifted off the upper edges of the foot end wall 6 and the side wall 4, into the upper part of the sweat box, so that the outer transverse rail 66 of the frame 61 rests upon the flange 64 of the upper edge member 63 35 of the end wall 6, and the longitudinal side rails 67 and 68 of said frame 61 rest upon the flanges 64 of the upper edge members 63, of the upper sections 16 of the side walls 4, respectively, with the pins 71 extending through the openings 72 40 in the flanges 64 in the edge members 63 of the upper sections 16 of the side walls 4; the top wall 7 is then unfolded, the frame 60 and the portion of the canvas sheet 62 extending over said frame being swung on the inner transverse rail 69 of said frame 60, as a pivot, up and away 45 from the frame 61 and the portion of the canvas sheet 62 over said frame, as shown in dotted lines in Fig. 1, until said frame 60 and the portion of the canvas sheet 62 extending over the same are 50 lowered into the top of the sweat box, so that the outer transverse member 65 of said frame 60 rests upon the flange 64 of the upper edge member 63 of the head end wall 5, and the longitudinal side rails 67 and 68 of said frame rest upon the flanges 64 of the upper edge members 63 of the upper sections 16 of the side walls 4, respectively, and as said frame 60 and the portion of the sheet 62 extending over said frame are lowered into the top of the sweat box upon said flanges 64, as 55 aforesaid, the head of the patient with a towel around his neck is extended through said frame 60 and through the head opening 73 in the sheet 62 over said frame, with said opening enlarged by having run the zipper 76 to the inner end of the slit 75, whereupon said zipper is run back over said slit to said head opening 73 and the sheet 62 at the edge of said opening is thereby closed upon the towel around the neck of the patient as shown in Fig. 1 of the drawings; the switch 42 60 being positioned within the box 2, is then closed

by the patient in the box and steam is generated by the heater 23 in the generator 22, which steam passes from said generator through the steam pipe 24 into the top of the condenser chamber 25 and into the sweat box below the false bottom 9, and the steam passes from below said false bottom upwardly into the sweat box, through the spaces 37 between the side edges of said false bottom and the side walls 4 of the sweat box, and through the space 36 between the foot end of said false bottom and the foot end wall 6 of the sweat box or through a space 36 between the head end of said false bottom and the head end wall 5 of the sweat box, according to the longitudinally adjusted position of said false bottom, which steam above said false bottom heats the air in the sweat box and supplies a moist atmosphere for the body of the patient reclining in the bed 10. The switch 12 may be opened by the patient and the steam generator 22 shut off when the heat in the sweat box becomes too hot.

While in the sweat box the patient may project his hands and arms through the arm openings 74 in the top wall 7 for using his hands and arms outside of the sweat box for any purpose as desired. The patient may then withdraw his arms and hands back into the sweat box through said arm openings 74 and the weighted flaps 77 will then automatically swing down over said openings to close the same.

When the patient has completed his sweat bath he opens the switch 12 and turns off the heat, and then runs down the zipper 76 to the inner end of the slit 75, to enlarge the head opening 73, and the frame 60 and portion of the canvas sheet 62 over said frame are swung upwardly on the inner transverse rail 69 of said frame and downwardly on said rail upon the frame 61 and the portion of the sheet 62 over said frame, and as said frame 60 and portion of the sheet over said frame are swung upwardly the head of the patient escapes through said frame 60 and through the enlarged head opening 73 in said portion of said sheet over said frame. The patient may then pull the chains 20, connected to the slide bolts 18 on the upper section 16 of one side wall 4 of the sweat box, and withdraw said bolts from catches 19 in the end walls 5 and 6 of the sweat box, whereupon said upper section 16 may be swung down on its hinge 17, and the patient may then get out of the bed 10 and step out of the sweat box through the upper part of the side of the sweat box which is opened by swinging down said upper section 16 of the side wall 4, as aforesaid.

The switch 12 controlling the heating circuit of the steam generator 22, when drawn into the sweat box through the enlarged opening 31 in the head end wall 5 of the sweat box may be held in a position within convenient reach of the patient reclining in the bed 10 for operation by the patient, by extending the wires 26 and 27, connected to said switch, upwardly through the frame 61 and over the transverse rails 69 and 70 of said frame 61 and the frame 60, respectively, of the top wall 1, and downwardly through said frame 60 and out of the sweat box through the opening 30 in the end wall 5 of the sweat box, as shown in full lines in Fig. 1 of the drawings.

The switch 28 is shown in dotted lines in Fig. 1 drawn out of the sweat box through the opening 31 in the head end wall 5 of the sweat box, in position to be operated by a nurse outside of the sweat box.

By means of my invention men and women may

get into my sweat boxes in their respective dressing rooms and rolled in the sweat boxes into a special room where they may remain together while taking their sweat baths in my sweat boxes, after which the men and women may be rolled back into their respective dressing rooms for rubbing and dressing.

I claim:

1. A sweat box including a box, a steam generator for generating steam and discharging the steam in said box, a bed in said box upon which a patient may recline, said bed comprising a head member, a foot member, a seat member, and a bottom member of flexible sheet material secured at its ends, respectively, to said head member and said foot member and extending over said seat member.

2. A sweat box including a box, a steam generator for generating and discharging steam in said box, a bed in said box comprising a head member, a foot member, a seat member, and a flexible sheet bottom member secured at its ends, respectively, to said head member and said foot member, said seat member comprising a seat bar extending transversely under the seat portion of said flexible bottom member, and means for supporting said seat bar in position.

3. A sweat box as claimed in claim 2, in which the means for supporting the seat bar in position comprises a pair of angle brackets secured to the inner side of the side walls, respectively, of the box, upon which brackets rest the ends, respectively of said seat bar, said brackets being provided with openings, respectively, therein, and pins extending downwardly from the ends, respectively, of said seat bar through said openings in said brackets, respectively.

4. A sweat box including a box, a steam generator for generating and discharging steam in said box, a bed in said box comprising a head member, a foot member, a seat member, and a flexible sheet bottom member, secured at its ends, respectively, to said head member and said foot member, said seat member comprising a seat bar extending transversely under the seat portion of said flexible bottom member and means for supporting said seat bar in different transverse positions under the seat portion of said flexible sheet bottom member.

5. A sweat box comprising a box, a bed mounted in said box, upon which a patient may rest, a false bottom of less length than the length of said box, legs on which said false bottom is pivotally mounted at its ends, respectively, which legs rest upon the bottom wall of said box and support said false bottom in said box below said bed, so that said false bottom may be swung longitudinally on said legs until one end of said false bottom engages the adjacent end wall of said box and the other end of said false bottom is spaced a short distance from the other end wall of said box, and a steam generator mounted in said box below said false bottom for generating steam and discharging the steam under said false bottom so that said steam will pass upwardly into said box through said space between said other end of said false bottom and the adjacent end wall of said box.

6. A sweat box comprising a box, a bed in said box upon which a patient may rest, a steam generator for generating and discharging steam in said box, said steam generator including an electric heater and a heating circuit controlled by a switch, said box being provided with a small opening and a larger opening communicating with said small opening, through which small opening ex-

tend the wires of said heating circuit and through which larger opening said wires and said switch may be drawn into said box or out of said box, so that said switch may be actuated by the patient when the switch is in the box or by an attendant when said switch is out of the box a cover plate and a pair of spring clips secured to said plate for engaging the edge of said larger opening for de-

tachably holding said plate over said larger opening.

7. A sweat box as claimed in claim 6 including a cover plate for normally covering the larger opening in the box through which the heating circuit wires and switch are drawn as described.

MILTON A. COTTER.
